UNITED STATES PATENT OFFICE.

NATHAN STEELE AND HAYES BROWN, OF COLUMBUS, OHIO.

MACHINE FOR WEAVING CROSS-WIRES IN FENCES.

SPECIFICATION forming part of Letters Patent No. 699,985, dated May 13, 1902.

Application filed April 27, 1901. Serial No. 57,682. (No model.)

To all whom it may concern:

Be it known that we, NATHAN STEELE and HAYES BROWN, citizens of the United States, residing at Columbus, in the county of Franklin and State of Ohio, have invented a certain new and useful Improvement in Machines for Weaving Cross-Wires in Fences, of which the following is a specification.

Our invention relates to the improvement of machines for weaving cross-wires in wire fences; and the objects of our invention are to provide an improved machine of this class of superior construction and arrangement of parts whereby the weaving of cross-wires in a wire fence may be rapidly and effectively accomplished, and to produce certain improvements in details of construction and arrangement of parts which will be more fully pointed out hereinafter. These objects we accomplish in the manner illustrated in the accompanying drawings, in which—

Figure 1 is a side elevation of our improved machine. Fig. 2 is a front elevation of the same. Fig. 3 is a central vertical section enlarged from the previously-described figures. Fig. 4 is a detail view showing a transverse section through two of the weaving-spools and illustrating the positions of the same when the wire-carrying reel is being transferred from one weaving-spool to the other. Fig. 5 is a sectional view through one end of the wire-carrying reel-frame, and Fig. 6 is an enlarged section on line $y-y$ of Fig. 1.

Similar numerals refer to similar parts throughout the several views.

In carrying out our invention we provide vertical and parallel frame side plates 1 and 2, which are suitably connected at their upper and lower end portions to produce the main weaver-carrying frame. Each of these frame side plates or standards is provided with a vertical row of circular openings 3, the latter gradually decreasing in size from top to bottom of the row and said openings being made to communicate in their upper and lower sides, as shown. In the oppositely-located openings 3 of the standards 1 and 2 are made to bear rotatably the disk-like heads 4 and 5 of weaver-carrying spools 6, the transverse shaft portions of each of the latter being provided with a longitudinally-slotted opening 7. Each of the heads 4 and 5 is formed on

its inner side with a disk-like enlargement, resulting in the formation of internal circular shoulders, these shoulders being indicated 55 at 4^a and 5^a. Each of the tubular shafts 6 has that end portion on which the head 4 is mounted, extended through said head and caused to bear in a bearing-opening formed in a vertically-arranged bar 8, which is secured on the outer side of the frame-standard 1. On the outer side of this bar the enlarged head of the shaft 6 carries a sprocket-wheel 9, said sprocket-wheel being formed with an opening 10, arranged out of center therewith 60 and larger than the central opening of the spool-shafts and communicating with the slotted opening 7 of the shaft 6. A similar offset or opening 10^a is formed in each of the spool-heads or disks 4 and 5, these larger 65 openings 10^a communicating with the bore of the corresponding spool-shaft, as indicated in Fig. 3. Each of the disks or heads 4 and 5 is formed with a peripheral notch 11, which extends inward to the periphery of the shoulders 4^a 5^a. 75

12 represents an oblong reel-frame within which is journaled transversely a wire-carrying spool or reel body 13. The ends of this reel-frame 12 are provided with outwardly-extending trunnions 14 and 15, the trunnion 15 being, as indicated more clearly in Fig. 5 of the drawings, in the nature of a tube. The trunnions 15 and 14 are adapted, as indicated in the drawings, to be supported, respectively, 80 in two oppositely-located spool-head notches 11, while the wire 13^a from the spool 13 is adapted, as shown in Fig. 6 of the drawings, to pass through the tubular trunnion 15. 85

On the inner sides of the standards 1 and 90 2 and on opposite sides of the points of connection of the openings 3 are pivoted inwardly-extending gravity pawls or fingers 16 and 17. Each of the pawls 16 has its inner pointed or wedge-like end portion normally 95 bearing by gravity upon the shoulder 4^a of the next lower spool-head 4 or 5, while the pawls or fingers 17 have their outer end portions weighted to insure the contact of the inner pointed portion thereof with the under side 100 of the shoulder 4^a or 5^a of the next higher spool-head 4 or 5, this construction being shown more clearly in Figs. 3 and 4 of the drawings.

Secured to the outer sides of the plates or standards 1 and 2 are parallel forwardly-projecting arms 18 and 19, and journaled between the outer ends of these arms is a shaft 20, on one end of which is carried a sprocket-wheel 21. The inner portion of the arm 18, in front of the standard 1, has pivoted thereon an idle sprocket-wheel 22. The shaft 20, as indicated at 23, carries an operating-crank. Through the medium of dotted lines in Fig. 1 of the drawings and in full lines in Fig. 2 I have indicated a continuous driving-chain 24, this chain running, as shown in Fig. 1, alternately over the rear and front sides of the sprocket-wheels 9 and running from the upper sprocket-wheel 9 downward beneath the sprocket-wheel 22 and over the sprocket-wheel 21, thence to the lower sprocket-wheel 9.

25 represents the parallel horizontal wires of a wire fence. These wires, as indicated in the drawings, are in utilizing my invention made to pass, respectively, through the tubular shafts of the spools 6, the main frame of our device being thus supported in a vertical position. In order to illustrate the operation of weaving cross-wires in connection with the horizontal wires 25, we will assume that the trunnions 14 and 15 of the wire-reel-carrying frame 12 are located, respectively, in the peripheral notches 11 of the upper oppositely-located reel-heads 4 and 5, and that that portion of the wire 13^a which extends outward through the trunnion 15 has been previously engaged with the top or upper horizontal wire 25. By turning the crank-handle 23, and thus through the chain 24 imparting rotary motion to the spools 6, which motion, we will assume, is such as to cause the upper spool to rotate in the direction indicated by the dotted arrow in Fig. 3, it is obvious that the wire-reel frame 12 may be made to travel about the shaft of the upper spool 6 the desired number of times, thereby causing the wire 13^a to be wound or coiled upon the upper wire 25 the desired number of times. In this operation it is obvious that at each rotation of the spool-heads 4^a 5^a the inner ends of the pawls 17 will be depressed during the passage of the trunnions 14 and 15 over the same. In order to move the reel downward in position to wind the wire 13^a on the next lower wire 25, the motion of the chain 24 is reversed, thus reversing the motion of the spools and causing the trunnions 14 and 15 of the reel-frame to move out of the notches 11 of the upper stool-heads and pass between the fingers or pawls

17 in the manner indicated in Fig. 4. In this manner the reel-frame is carried into connection with the notches 11 of the next lower spool-heads, and through its traveling action 60 about said next lower spool results in the wire 13^a being wound upon the next lower wire 25. It is obvious that the operation of transferring the wire-carrying reel from one spool to another may be continued throughout the 65 spools of the vertical row to the bottom of the frame, after which the frame may be made to slide in the direction of the length of the wires 25 and the operation of successively connecting the cross-wire 13^a with the horizontal wires carried on by such rotary movement of the spools as will result in carrying the reel upward.

In cases where the horizontal fence-wires have been spliced or enlargements formed 75 therein by kinking or otherwise it is obvious that any difficulty which might be experienced through the failure of the wire where these enlargements occur to pass through the tubular shafts of the spools 6 may be remedied by forcing the wire temporarily out into the larger sprocket-wheel openings 10 or until the obstruction is passed.

From the construction and operation described it will be seen that a machine is provided for weaving cross-wires in fences by which the operation may be carried on rapidly and effectively.

Having now fully described our invention, what we claim, and desire to secure by Letters 90 Patent, is—

In a machine for weaving cross-wires in fences, the combination with a framework comprising vertical frame-standards and spools 6 having enlarged heads journaled in 95 said frame-standards, said heads having peripheral notches 11, the shafts of said spools being tubular and a gear connection between the outer ends of said shafts, of a reel-frame 12 having journaled therein a wire-carrying 100 spool, said frame 12 having trunnions 14 and 15, the latter being tubular, said trunnions adapted to engage oppositely-located notches of the spool-heads 4 and 5, and means for directing said trunnions from the notches of 105 one pair of heads into the notches of an adjacent pair, substantially as specified.

NATHAN STEELE.
HAYES BROWN.

In presence of—

C. C. SHEPHERD,
P. S. KARSHNER.
